UNITED STATES PATENT OFFICE.

HARRIET E. MANCHESTER, OF BUFFALO, NEW YORK.

DESIGN FOR A CHRISTMAS-BOOK.

SPECIFICATION forming part of Design No. 11,970, dated September 28, 1880.

Application filed July 23, 1880. Term of patent 3½ years.

To all whom it may concern:

Be it known that I, HARRIET E. MANCHESTER, a citizen of the United States, residing at Buffalo, in the county of Erie and State of 5 New York, have invented and produced a new and original Design for a Christmas-Book, of which the following is a specification, reference being had to the accompanying drawing, forming part thereof, which represents an elevation, partly in perspective, of my newly-designed book, representing, in outline and shape, a stocking—that is, the two covers will be formed to represent a stocking—and to further carry out the idea, will be printed and colored 10 to imitate the colored hose now generally in use. At the top a ribbon is passed through and around the leg of the stocking to represent a garter, which will be tied in a bow or loop. Inside—that is, between the outer 15 colored representations of a stocking—are a number of leaves conforming in shape to the covers, on which will be printed poetry, extracts, &c., relating to Christmas and Christmas-stockings, &c., and with or without illustrations.

The leading feature of my design is a book having the shape or contour of a stocking. The ornamentation of the stocking may be varied or all the same.

A and A' represent the two covers formed in 30 the shape of a stocking; a a, the leaves between, and b the garter and bow or loop.

I claim—

The design for a Christmas-book herein shown and described, the same consisting of 35 covers A, formed in the shape of a stocking, which inclose leaves of a similar shape, the whole confined by a ribbon in the upper corner, formed into a loop or loops, and representing a garter, all substantially as specified. 40

In witness whereof I have hereunto signed my name in the presence of two subscribing witnesses.

HARRIET E. MANCHESTER.
